JAMES BAIN, OF BROOKLYN, E. D., NEW YORK

Letters Patent No. 66,281, dated July 2, 1867.

IMPROVED VENT-PLUG.

The Schedule referred to in these Letters Patent and making part of the same.

TO ALL WHOM IT MAY CONCERN:

Be it known that I, JAMES BAIN, of Brooklyn, in the county of Kings, in the State of New York, have invented a new and useful Improved Vent-Plug; and I hereby declare that the following is a full, exact, and clear description thereof, which will enable those skilled in the art to make and use the same, reference being had to the accompanying drawing, forming part of this specification, in which drawing—

Figure 1 represents a longitudinal central section of this invention.

Figure 2 is a transverse section of the same, taken in the plane indicated by the line $z z$, fig. 1.

Figure 3 is a similar section of the same, the line $q q$, fig. 1, indicating the plane of the section.

Similar letters of reference indicate corresponding parts.

This invention relates to a vent-plug which is provided with a valve that is adjustable by means of a screw-rod and spring, and fitted into a seat in the inner end of the plug, which is perforated with suitable vent holes in such a manner that when the pressure of the external atmosphere exceeds the pressure of the atmosphere in the interior of the barrel, combined with the power exerted by the spring, the valve is forced open and a sufficient quantity of air is permitted to enter to cause the liquid to discharge from the barrel, and by adjusting the power of the spring the valve can be set, and the quantity of air admitted into the barrel can always be reduced to the minimum or to the exact quantity required to cause the contents of the barrel to discharge.

The valve-seat is made removable, so that the same, together with the valve, can be readily taken off for the purpose of cleaning. The outer end of the plug is provided with an air-chamber and an adjustable cap, by means of which the supply of air to the barrel can be regulated or stopped at pleasure.

A represents a plug, which may be made of wood, metal, or any other suitable material, and which is secured in the barrel by a screw-thread or in any other suitable manner. This plug is bored out, as clearly shown in fig. 1 of the drawing, and its inner end forms the seat B for the valve C. The stem of this valve extends up into the cavity of the plug, and its end is provided with a screw-thread on which is fitted the nut a . Between this nut and the inner surface of the seat B is placed a spring, b , which presses against the nut and has a tendency to keep the valve C in its seat. By turning the nut a up or down the power of the spring is decreased or increased, and the valve is held in its seat with greater or less force. If the pressure of the gases in the interior of the barrel decreases to such an extent that the external pressure of the atmosphere is able to overcome said internal pressure together with the force of the spring b , a sufficient quantity of air passes into the barrel to cause the contents thereof to discharge, and as soon as the internal pressure reaches a certain point the valve closes and the communication with the external atmosphere is stopped up. By adjusting the force of the spring the time when the valve closes can be regulated at pleasure, and all loss of gases from the interior of the barrel is prevented, and at the same time the contents of the barrel are preserved from the injurious influence of the atmospheric air. The seat B is secured in the plug by a screw-thread, or in any suitable manner, so that the same, together with the valve, can be readily removed for the purpose of cleaning, or that a metallic seat can be attached to a wooden plug. The outer end of the plug is bored out to form an air-chamber, D, which communicates with the external atmosphere through a series of holes, c , and with the cavity of the plug through an aperture, d , in the transverse partition. Said air-chamber is furnished with a screw-cap, E, which is provided with a broad flange, f . If this cap is screwed clear down, the flange f bears tight upon the external surface of the barrel and prevents dirt from getting into the air-chamber, and the inner end of the cap bears air-tight against a washer on the bottom of the air-chamber, and thereby the communication between the interior of the barrel and the external atmosphere is effectually stopped, and the loss of any portion of the contents of the barrel by leakage through the plug is prevented, and no air is permitted to pass into the barrel. By unscrewing the cap more or less, the quantity of air which is permitted to enter the barrel can be regulated.

By this means a vent-plug is obtained which is not liable to get out of repair, and which effectually protects the contents of the barrel against the injurious influence of the atmospheric air.

What I claim as new, and desire to secure by Letters Patent, is—

1. The valve C, nut a , and spring b , in combination with the seat B in the inner end of the plug A, substantially as and for the purpose described.
2. The movable seat B, in combination with the valve C, nut a , spring b , and plug A, substantially as and for the purpose set forth.
3. The air-chamber D and cap F, in combination with the plug A and valve C, constructed and operating substantially as and for the purpose described.

JAMES BAIN.
